ROTARY PUMP

Donald A. Fulton, Los Angeles, Calif.

Application September 18, 1939, Serial No. 295,423

13 Claims. (Cl. 103—124)

My invention relates generally to rotary pumps, and more particularly to pumps designed for compressing a gaseous or mixed gaseous and liquid refrigerant.

A somewhat similar form of pump is disclosed in my copending application, Serial No. 133,864, filed March 30, 1937, now Patent No. 2,198,382, issued April 23, 1940, and the present application relates to a pump having certain modifications and improvements over the previously-described device.

It is a major object of this invention to provide a rotary-type compressor, having a positive displacement and requiring a minimum number of moving parts.

It is a further object of my invention to produce a compressor of the rotary type which is compact, efficient, dependable, and has a long life.

These and other objects of my invention will become apparent from the following description of preferred forms thereof, and from the drawings illustrating those forms, in which:

Fig. 1 is an axial cross-sectional view of one form of compressor made according to my invention.

Fig. 2 is a cross-sectional view taken at 2—2 in Fig. 1.

Fig. 3 is an axial cross-sectional view of another form of compressor embodying my invention, and

Fig. 4 is a cross-sectional view taken at 4—4 in Fig. 3.

Referring now to the drawing, and particularly to Fig. 1 thereof, the numeral 10 indicates a housing provided with a cylinder 11 open at one end (the left end in Fig. 1). A cap 12 is bolted or otherwise securely fastened over the open end of cylinder 11 closing it with a sealing fit. The end of the cylinder formed by the housing 10 is preferably normal to the axis of the cylinder and is provided with a convex conical surface 13 (hereinafter referred to as the cone 13) coaxial with the cylinder 11 extending into the same. The diameter of the base of the cone 13 is somewhat less than that of the cylinder 11 thus leaving a small annular shoulder 14 surrounding the base of the cone.

Within the cylinder 11, and making a sealing fit with the wall and shoulder 14 thereof, I provide a rotor 15, to which is attached a shaft 16 extending outwardly through the cap 12. To provide a sealing fit, the rotor has a cylindrical shape, and to make even more certain that a fluid-tight seal is obtained, I may provide grooves 17 and 17a around the periphery of the rotor and

insert sealing rings 18 and 18a therein. It will be apparent that a greater or lesser number of sealing rings may be used, as will be pointed out more fully hereinafter, or that other types of sealing means may be used; however, I have found the means illustrated to be a very satisfactory method and give it by way of example.

In order for the rotor 15 to bear against the shoulder 14 of the recess 11, it is necessary to provide the end face of the rotor with a recess into which the cone 13 may fit. It is this recess within the end of the rotor, together with the cone 13 which provides the compressor action of my device. I am aware that others have developed pumps for liquids making use of a convex cone-shaped surface against which an obliquely truncated cylinder bears, but such pumps are not suitable for gas compressors of the type used for refrigerators because of the high pressures involved and the resultant leakage of gas. To overcome these disadvantages, I form the end surface of the rotor 15 in the shape of an obliquely-positioned concave cone 20 whose apex is substantially coincident with the apex of the cone 13, and the length of whose side is equal to the length of the side of cone 13.

The shape and aspect of the conical surface 20 is such that it provides a cam-shaped end surface, one of whose generating elements makes 20 wiping contact with the cone 13, said element being hereinafter referred to as the high point of the end surface 20. The base of the concave conical surface 20 is a plane circle angularly-positioned with respect to both the shoulder 14 and the axis of the rotor 15, and hence must lie within the body of the rotor except at the high point. This requirement necessitates a lip 21 of varying height, and for reasons which will be apparent later, the inner surface of this lip should be shaped in the form of a portion of a sphere whose center is at the apex of the concave conical surface 20 and whose radius is equal to the length of one of the sides of that cone.

Thus there is formed a chamber of constant volume between the cone 13 and the concave conical end surface 20; and as the rotor 15 is revolved, the position of the chamber revolves with it but does not change in volume, since the angular aspect of the end surface 20 with respect to the axis of the rotor does not vary. Any fluid within the chamber would therefore be carried around with the rotor and neither compressed nor expanded. However, if a plate 22, in the form of a minor circular sector whose apex angle is equal to the apex angle of the concave conical surface

20 and whose radius is equal to the length of one of the sides of said conical surface, is placed in a slot 23 extending diametrically across the cone 13 and shaped in the form of a sector of the same circle as that of the plate 22, the latter will divide the chamber into two or three chambers, depending on the location of the high point of the end surface 20. The plate 22 is free to oscillate back and forth in an arc of the circle of which it is a sector; and since its apex angle is equal to the apex angle of the end surface 20, the radial edges of the sector will bear and wipe against the end surface at all times. Thus as the high point of the end surface 20 approaches one of the radial edges of the plate 22, that edge is forced into the body of the cone 13, and the other radial edge moves out of the cone and wipes against the concave conical end surface 20, until the high point contacts the first-mentioned radial edge of the plate 22, when that edge of the plate is in its innermost position, and the other radial edge is in its outermost position.

It will now be seen that as the radial edge of the plate 22 moves outwardly and into the rotor 15, a portion of its arcuate edge follows it and extends out from the cone 13 and into the rotor, wiping against the inner surface of the lip 21. For this reason, since the arcuate edge is formed in the shape of a portion of an arc of a circle, and the rotor 15 revolves about an axis perpendicular to the axis of the arc of the circle of the plate, it is necessary for the inner surface of the lip 21 to be formed in the shape of a portion of a sphere in order for the plate 22 to make sealing contact with it.

In order for the device to function as a compressor, it is necessary to provide intake and outlet means so that fluids may enter and leave the chambers formed by the conical surfaces 13 and 20, lip 21, and the oscillating plate 22. In Fig. 1, I have illustrated one method of doing this which is particularly well adapted for use with the sealing means shown there. In this method, I provide the periphery of the rotor 15 with grooves 24 and 25, hereinafter referred to as the intake and outlet grooves, respectively; and aligned with these grooves, I provide apertures 26 and 27 in the housing 10 leading to intake and exhaust connections 28 and 29, respectively. A short distance from the high point of the end surface 20, measured in the direction opposite from the rotation of the rotor 15, a passageway 30 leads from the end surface 20 to the intake groove 24, and a similar passageway 31 leads from a point a short distance in advance of the high point of the cam-shaped surface to the exhaust groove 25.

Thus as the rotor 15 revolves and the high point of the end surface 20 passes over the plate 22 and continues on, an expanding chamber is created behind the high point, bounded by the end surface 20, the convex conical surface 13, the inner surface of the lip 21, and the plate 22. As the volume of the chamber increases, the suction created thereby causes fluid to flow in through the inlet passageway 30 and fill the expanding chamber. This continues until the passageway 30 crosses the opposite radial edge of the plate 22, when the same action takes place on the opposite side of the plate. As the rotor then revolves for approximately one half a revolution, the volume of the first chamber increases somewhat because of the oblique aspect of the end surface 20. Then when the high point of the cam-shaped surface again crosses the plate 22 into the first-mentioned chamber, the high point wipes against

the convex conical surface 13 and decreases the volume of the chamber, compressing any fluid therein and forcing it out the exhaust passageway 31. At the same time, fluid is being drawn into an expanding chamber immediately behind the high point as first described. This cycle is completed twice each revolution of the rotor 15, once on either side of the plate 22, and thus a substantially constant flow of fluid is maintained.

As the rotor 15 revolves, the fluid is drawn into the chamber between the end surface 20 and the cone 13, and then compressed, as previously described. However, because of the increase of volume of the first chamber after the intake passageway 30 has passed the plate 22, more fluid may be drawn into that chamber, and hence to secure the maximum efficiency of the compressor, I prefer to provide an auxiliary intake passageway 30a, spaced approximately diametrically opposite from the outlet passageway 31 so that both will not be open to the same chamber at the same time. Thus after the main intake passageway 30 has crossed the plate 22 into the other chamber, the auxiliary intake passageway 30a remains open to the first chamber, permitting a pressure equilibrium to be established between the first chamber and the supply line.

It will be apparent that for the proper functioning of the device, it is important that a fluid-tight seal be maintained between the plate 22, and the end surface 20 so that fluid being compressed on one side of the plate will not escape to the opposite side of the plate where fluid is being drawn in. It is to provide this fluid-tight seal that I have made the end surface 20 in the form of an oblique cone, for in this way, I am able to transversely curve the radial edges of the plate 22 to conform to the curvature of the concave conical surface 20. By thus curving the plate 22, I provide an area of contact instead of a line of contact between the plate and the concave conical surface 20. If the end surface 20 were made in the form of an obliquely truncated cylinder, the plate would make only a line contact with the end surface and much of the sealing effect would be lost. Others have attempted to use truncated cylinders and overcome said disadvantage by providing an auxiliary pivoted wiping plate attached to the sector plate and making sealing contact with the cam-shaped surface, but such devices have proven impractical, and are unnecessary in my type of rotor employing a cone-shaped surface.

The apex angle of the cone 13 is not critical, though it is preferable that it be of such a value that the sides of the cone do not present a very sharp angle to the plane of the lip 21. If this latter angle is too acute, any slight amount of wear of the end of the rotor 15 will permit an excessive amount of leakage, while if the angle is not so acute, leakage is kept to a minimum. The size and aspect of the apex angle of the concave conical surface will be determined to a certain extent by the size of the apex angle of the cone 13, since the high point of the cam-shaped surface 20 must make sealing contact with the cone 13. The apex angle of the concave conical surface 20 will of course determine the apex angle of the plate 22, but the other angles may be varied. The relative sizes of the apex angles of the conical surfaces 13 and 20 and the length of their sides will determine the displacement of the compressor, which, of course, may be varied over wide limits.

As previously mentioned, sealing rings 18 and

.18a are placed in grooves 17 and 17a around the periphery of the rotor, and serve the double purpose of sealing the fluid within the chamber formed by the two conical surfaces 13 and 20, and also preventing the escape of the compressed fluid from the exhaust groove 25 to the intake groove 24. If the pressure in the intake groove 24 is substantially above or below atmospheric pressure, it may be advisable to place a sealing ring or rings between it and end of the rotor 15; and likewise it may be preferable to place a plurality of sealing rings between the intake and outlet grooves 24 and 25 and/or between the outlet groove 25 and the inner end of the rotor 15. Such considerations, of course, will depend upon the pressures involved and the closeness of fit between the rotor 15 and the housing 10, and will be apparent to those skilled in the art.

Because of the mechanical problems involved, it may be difficult to form the inner surface of the lip 21 in the shape of a portion of a sphere; and hence in Figs. 3 and 4, I show a form of compressor made according to my invention in which I dispense with said lip. The form illustrated in said figures is similar in most respects to the form shown in Figs. 1 and 2, and has a housing 10, a cap 12, a cone 13, a rotor 15 to which is attached a shaft 16, an obliquely-positioned concave conical surface 20, a plate 22 in the form of a minor circular sector, and a slot 23 in the cone 13 in which the plate 22 is located, as previously described in detail. Instead of the cylinder 11, however, this form of my compressor is provided with a chamber 40 shaped in the form of a portion of a sphere having its axis coincident with that of the rotor 15. The periphery of the rotor 15 adjacent the end surface 20 is therefore complementally shaped so as to provide a sealing fit with the walls of the recess 40. The radius of the spherical surfaces is equal to the length of the sides of the conical surfaces 13 and 20, and the center is coincident with the apices of the two conical surfaces. Hence, since the plate 22 has the same radius and center, it will make a sealing and wiping fit with the spherical surface 40 of the housing 10, and a similar fit with the end surface 20 of the rotor 15. In this way, I have eliminated the need for the lip 21 and shoulder 14, or as an alternative, the need for a groove in the side of the chamber in which the plate 22 may move when a cylindrical chamber and rotor are used. The need for a groove in the side of the chamber in lieu of the lip 21, will be apparent when it is remembered that the end surface 20 is obliquely positioned and the rotor is a cylinder; and hence the distance along the cam-shaped surface from the apex of the cone to the edge of the rotor will vary as the angle the end surface 20 makes with the side of the rotor varies. Therefore, since the plate 22 must make sealing contact with the end surface 20 along its greatest dimension as well as all others, provision must be made for the excess length of the radial edge of the plate 22 to move into the walls of the housing 10 when it is not needed.

If recourse is had to the side groove just mentioned, there will be a line of contact between the rotor 15 and the plate 22 preventing the fluid from escaping through the groove and around the plate, and as soon as there has been a sufficient amount of wear, the compression is lost. To avoid this difficulty, I have found it best to use either the lip and shoulder method shown in Figs. 1 and 2, or preferably, the spherically-shaped rotor of Figs. 3 and 4.

In conjunction with the latter form, I have shown an additional type of sealing means, it being understood of course that either sealing means may be used with either form of my compressor. In the form of sealing means illustrated in Figs. 3 and 4, the rotor 15 takes the shape of a hemisphere with an obliquely-positioned sector of the sphere removed, and adjacent the hemispherical portion may be located a cylindrical portion of the same diameter as the hemispherical portion and concentric therewith, extending backwardly toward the shaft 16 a short distance. The only function of the cylindrical portion is to add mechanical strength to the rotor, and hence if it were desired, that portion might take the form of a truncated cone. The cap 12 is provided with annular grooves 41, 42, and 43, grooves 41 and 43 being designated as intake and outlet grooves respectively. Radially aligned with their respective grooves are the intake passageways 30 and 30a and the outlet passageway 31, and connected to the grooves by appropriate means are the intake and outlet connections 28 and 29, respectively.

Between the grooves 41 and 43 is the groove 42, and aligned with the latter groove is an annular ridge 44 on the outer face of the rotor 15 which fits into the groove 42 and provides a seal between the intake groove 41 and the outlet groove 43. Obviously, other grooves and ridges may be added as required, as for example, between the inlet groove 41 and the edge of the rotor 15, or between the outlet groove 43 and the shaft 16.

My compressor finds its greatest use in refrigerating systems in which a material in a gaseous phase or in gaseous and liquid phases is compressed to a liquid phase, but it is not limited to this field. It will be apparent that various materials may be used in the manufacture of the compressor and that various dimensions may be used, depending upon particular conditions. It is to be understood that my invention is not to be limited to the specific forms or arrangement of parts herein described and shown, or specifically covered by my claims.

I claim as my invention:

1. A rotary compressor which includes: a housing; a member in said housing having a concave conical end surface whose axis is obliquely positioned with respect to the axis of said member and whose base is a plane circle obliquely positioned with respect to the axis of said member; a cone within said housing and axially aligned with said first member; a movable plate in the form of a minor circular sector making a wiping contact with said end surface and extending diametrically across said cone to form with said cone, said end surfaces, and the walls of said housing, a chamber of variable volume; and means to admit and discharge fluid into said chamber of variable volume, said conical surfaces being rotatable with respect to each other.

2. A compressor as described in claim 1 in which said concave conical end surface is surrounded by a lip of varying height whose inner surface is shaped in the form of a portion of a sphere.

3. A compressor as described in claim 1 in which the periphery of said first member adjacent its concave conical end surface is shaped in the form of a portion of a sphere whose radius is equal to the length of the side of said concave conical surface and whose center is at the apex of said conical surface.

4. A rotary compressor which includes: a housing; a member in said housing having a concave conical end surface whose axis is obliquely positioned with respect to the axis of said member and whose base is a plane circle obliquely positioned with respect to the axis of said member; a cone within said housing coaxial with said first member and against which the high point of said end surface wipes; a movable plate in the form of a minor circular sector, making wiping contact with said end surface and extending diametrically across said cone, said plate forming with the walls of said housing, said concave surface, and said cone a chamber of variable volume; and means to admit and discharge fluid into said chamber, said conical surfaces being rotatable with respect to each other.

5. A compressor as described in claim 4 in which said concave conical end surface is surrounded by a lip of varying height whose inner surface is shaped in the form of a portion of a sphere.

6. A compressor as described in claim 4 in which the periphery of said first member adjacent its concave conical end surface is shaped in the form of a portion of a sphere whose radius is equal to the length of the side of said concave conical surface and whose center is at the apex of said conical surface.

7. A rotary compressor which includes: a housing; a rotor in said housing having a concave conical end surface whose axis is obliquely positioned with respect to the axis of said member and whose base is a plane circle obliquely positioned with respect to the axis of said member; a cone in said housing coaxial with said rotor and against which the high point of said end surface wipes; a movable plate in the form of a minor circular sector whose center is coincident with the apex of said cone, and whose radius is equal to the length of the side of said end surface and making wiping contact therewith, said plate forming with the walls of said housing and said concave and convex conical surfaces a chamber of variable volume; means for admitting fluid to said chamber while it is expanding; and means to permit fluid to be expelled from said chamber while its volume is being decreased.

8. A compressor as described in claim 7 in which said concave conical end surface is sur-

rounded by a lip of varying height whose inner surface is shaped in the form of a portion of a sphere.

9. A compressor as described in claim 7 in which the periphery of said rotor adjacent its concave conical end surface is shaped in the form of a portion of a sphere whose radius is equal to the length of the side of said concave conical surface and whose center is at the apex of said conical surface.

10. A compressor as described in claim 7 in which said rotor is provided with sealing means around its periphery to prevent the escape and intermingling of influent and effluent fluids.

11. A rotary compressor which includes: a housing; a rotor in said housing having a concave conical end surface whose axis is obliquely positioned with respect to the axis of said member and whose base is a plane circle obliquely positioned with respect to the axis of said member; a cone in said housing coaxial with said rotor and against which the high point of said end surface wipes; a movable plate in the form of a minor circular sector whose center is coincident with the apex of said cone and whose radius is equal to the length of the side of said end surface and making wiping contact therewith, said plate forming with the walls of said housing, said end surface, and said cone a chamber of variable volume; means for permitting fluid to enter said chamber while it is expanding; means to permit fluid to be expelled from said chamber while its volume is being decreased; and sealing means including a groove with a sealing member therein between said fluid inlet means and said fluid outlet means.

12. A compressor as described in claim 11 in which said concave conical end surface is surrounded by a lip of varying height whose inner surface is shaped in the form of a portion of a sphere.

13. A compressor as described in claim 11 in which the periphery of said first member adjacent its concave conical end surface is shaped in the form of a portion of a sphere whose radius is equal to the length of the side of said concave conical surface and whose center is at the apex of said conical surface.

DONALD A. FULTON
